LATCHING MECHANISM

John B. MacNeill, Wilkinsburg, and John W. May, Forest Hills, Pa., assignors to Westinghouse Electric & Manufacturing Company, East Pittsburgh, Pa., a corporation of Pennsylvania

Application May 14, 1936, Serial No. 79,670

14 Claims. (Cl. 200—109)

This invention relates to latching mechanisms for circuit interrupters.

In circuit interrupters, the operating mechanism for actuating the contact members through a switching operation is usually held in a biased position by means of a latching mechanism to maintain the contact members in a contact making position. The latching mechanism is operative to release the actuating mechanism upon the occurrence of predetermined electrical conditions to cause the actuation of the contact members to an open circuit position.

In order to retain the actuating mechanism in a closed circuit position, the latching mechanism usually consists of heavy complicated linkages designed to withstand the reactive pressures exerted by the actuating mechanism when in closed position. Because of the complicated design of the latching mechanism and the large mass of parts which must be moved when the latch is tripped, the tripping movement is not transmitted to the actuating mechanism until three or more cycles after the tripping movement is initiated. This slowness in effecting the tripping sometimes results in damage to valuable apparatus connected in the circuit designed to be protected by the circuit interrupter.

An object of this invention is to provide a quick acting latching mechanism for a circuit interrupter to obtain high speed operation.

Another object of this invention is to provide a latching mechanism for a circuit interrupter, the members of which are independently mounted and are disposed for small angular movement to obtain high speed operations.

This invention accordingly is disclosed in the embodiment thereof shown in the accompanying drawings and comprises the features of construction, combination of elements and arrangement of parts which will be exemplified in the construction hereinafter set forth and the scope of the application of which will be indicated in the appended claims.

For a fuller understanding of the nature and objects of the invention, reference may be had to the following detailed description, when taken in conjunction with the accompanying drawings, in which:

Figure 1 is a view, partly in side elevation and partly in section, illustrating the latching mechanism of this invention as applied to the operating mechanism of a circuit interrupter;

Fig. 2 is a plan view of the latching mechanism in conjunction with the trip-free elements of the actuating mechanism of a circuit interrupter;

Fig. 3 is a view taken along the line III—III of Fig. 2;

Fig. 4 is a view taken along the line IV—IV of Fig. 2; and

Figs. 5 and 6 are side elevational views of a portion of the operating mechanism shown in Fig. 1 illustrating the position of the trip-free elements of the circuit interrupter.

Referring to the drawings, and Fig. 1 in particular, the latching mechanism 10 of this invention is shown carried on the frame 12 of the operating mechanism for cooperating with the operating levers 14 to retain them in a closed circuit position.

As an example and in order to facilitate the disclosure of this invention, a portion of the operating mechanism of one of the well known circuit interrupters is illustrated in detail in the drawings, it being understood that the latching mechanism of this invention may be employed with any of the trip-free circuit interrupters in which the operating mechanism and the contact members are normally biased to an open circuit position when in the closed circuit position.

The contact members and actuating levers (not shown) of the circuit interrupter are connected through an operating bar 16 to a lever 18 by means of a pin 20. The lever 18 carries a trip-free bar or roller 22 pivoted in one end of the lever and adapted to be engaged by the latching mechanism 10, as will be explained hereinafter.

In order to provide a pivot point about which the lever 18 may rotate during an opening movement of the operating bar 16, the lever 18 is pivotally connected to a lever 24 by means of a pivot pin 26. The lever 24 is pivotally anchored to the frame 12 of the circuit interrupter by the pin 28.

When in the closed circuit position, the lever 24 is biased for movement in a clockwise direction about its pivot point 28 by means of the retrieving spring 30 positioned between the lever 24 and the frame 12. One end of the spring 30 is securely anchored by means of the bracket 32 to the lever 24, while the other end of the spring 30 abuts the frame 12 and may be maintained in that position by any suitable means.

A latch 34 is carried by the frame 12 and is biased by means of a spring 35 to engage the pin 26 linking the levers 18 and 24 to retain them in the position shown in full lines in Fig. 1. In order to cause the latch 34 to release the pin 26 during a tripping movement of the mechanism, the lever 18 carries a projection 36 on its end adjacent the pin 26 for contacting a projection 38 carried

on the latch 34 when the lever 18 is rotated to a predetermined position about its pivot point 28. This causes the latch 34 to rotate in a clockwise direction about its pivot point 40.

- 5 When the latch 34 is rotated a predetermined distance, it releases the pivot pin 26, and the reactive force of the compressed spring 36 causes the lever 24 to rotate in a clockwise direction about its fixed pivot point 28 to the position shown 10 in dotted lines in Fig. 1. During this movement of the lever 24, the lever 18 rotates about the pivot pin 26 in a clockwise direction to return the free end of the lever 18 to the position shown in Fig. 6 where the trip-free bar or roller 22 may be 15 latched by the latching mechanism 10.

In order to actuate the mechanism to a closed circuit position, the lever 24 is pivotally connected to the armature 42 of an electromagnet 44 by means of a link 46. One end of the link 46 is 20 pivotally connected to the lever 24 by a pin 48 and the other end is pivotally connected to the armature 42 of the electromagnet 44 by means of a pin 50.

When the electromagnet 44 is energized, the 25 solenoid 42 and link 46 are actuated downwardly to rotate the levers 18 and 24 in a counterclockwise direction about the trip-free roller 22 and the pivot point 28 to the position shown in full lines in Fig. 1 of the drawings. 30 In moving to this position, the pivot pin 26 is engaged by the latch 34 so that the levers 18 and 24 are retained in closed circuit position.

In the particular operating mechanism illustrated, the trip-free roller 22 is carried between 35 two of the levers 18 which are suitably braced by means of a bar 52 therebetween. In order to provide a suitable pivot point 28 for the levers 18, two levers 24 are provided for supporting the pivot pin 26 and are held in spaced 40 relation by means of the bar 54. The bar 54 further acts as a support for the links 18 to prevent excess movement of the levers 18 and to cause the roller 22 carried by the levers 18 to align with the pivot pin 26 when the levers 24 45 are in the position shown in Fig. 6, or in full lines in Fig. 1.

When the operating mechanism is in the closed circuit position shown in full lines in Fig. 1, the roller 22 is engaged by an L-shaped engaging 50 lever or member 56. The engaging member 56 is pivotally carried on the frame 12 of the device by means of the pin 58 and is biased to an operative position by means of a spring 60 to engage the roller 22. The ends of the spring 60 are set into flat bottom cylindrical recesses or 55 wells 62 and 64 in the lever 56 and the frame 12, respectively.

In order to retain the lever 56 in its operative 60 position to engage the roller 22, a lever 66 is provided for cooperatively engaging the lever 56. The lever 66 is pivotally mounted at one end to the frame 12 by means of the pin 68. The other end of the lever 66 normally rests on the free end 70 of the lever 56 and carries a notch 65 70 for engaging the cooperating surface 72 on the engaging lever 56 to retain it in a latched position.

In order to insure the engagement of the lever 66 with the lever 56, the lever 66 is biased in a 70 counterclockwise direction about the pin 68 by means of springs 74 and 76. The spring 74 is suitably disposed between the lever 66 and a bracket 78 carried by the frame 12.

Since the biasing force of the springs 74 and 75 76 are not strong enough to retain the levers

66 and 56 in their operative position to retain the biased operating mechanism in a closed circuit position, a latch 80 is provided for latching the members in their engaging positions. The latch 80 is carried on one arm of a bell crank 5 82 which is pivotally mounted to the frame by means of a pin 84. The latch 80 is normally biased to its latched position by the spring 76 which is carried between the lever 66 and the arm 83 of the bell crank 82. In practice, the 10 lever 66 is provided with a cutout portion 86 through which the arm of the bellcrank 82 carrying the latch 80 projects to engage the top of the lever 66.

In order to insure a positive movement of 15 the lever 66 in a clockwise direction about its pivot point 68 to disengage the lever 56 during a tripping movement of the latching mechanism, a projection 88 is carried on the arm 83 of the bellcrank 82 for abutting a projection 90 carried 20 on the under-surface of the lever 66.

The latch 80 carried by the bellcrank 82 may be actuated to disengage the lever 66 by means of a force applied to the arm 83 of the bellcrank to rotate it in a counterclockwise direction about 25 the pin 84. The force may be applied to the arm 83 of the bellcrank by any suitable means. In practice, an electromagnet 90 is carried on the framework 12 of the device and is adapted, when energized in response to predetermined 30 electrical conditions, to actuate the solenoid 89 in an upward direction to strike the arm 83 and cause the latch 80 to release the lever 66.

As shown in Figs. 3 and 4, the solenoid 89 is also adapted to be actuated manually through 35 the use of a lever 92 pivotally carried on the frame 12 by the pin 94. The lever 92 may comprise two parallel bars suitably fastened together and presenting a forked end 93 at one end thereof. In order to guide the lever 92 when 40 it is actuated, a bolt 100 is so carried on the frame 12 that it extends in an upward direction in the opening of the forked end 93 of the lever 92. An intermediate member 98 is loosely seated on the end of the bolt 100 between the guides 102 carried on the frame and is adapted to be so moved 45 when the lever 92 is actuated as to actuate the solenoid 89 to strike the bell crank 82 and trip the latching mechanism. The lever 92 is normally biased to its inoperative position by means 50 of a spring 96 suitably mounted between the lever and the frame 12.

A means is provided for preventing resetting 55 of the latches after their release, until the roller 22 has been returned to its predetermined latched position. This means comprises a retrieving pawl 104 which is pivotally mounted on the frame 12 by means of a pin 106. The end 108 of the pawl is provided with a sliding contact surface 108 which is adapted to be engaged by the roller 22 as it is moved to latching position. The pawl 104 is normally biased in a clockwise direction about its pivot pin 106 by means of a spring 110 suitably mounted between the frame 12 and the end 108 of the pawl. 60

The spring 110 which biases the pawl 104 in a clockwise direction about the pin 106 is stronger than the spring 60 which biases the engaging lever 56 in a counterclockwise direction about its pivot point 58, so that as the roller 22 moves 70 to its unlatched or open circuit position, the pawl 104 rotates and forces the engaging member 56 to rotate in a clockwise direction into engagement with a resilient stop or bumper 112 suitably mounted on the frame 12. In this posi- 75

tion, the lever 66 is inoperative to engage the trip free bar or roller 22 to retain it in a latched position.

In operation, the roller 22 may be released from the latched position shown in Fig. 3 to release the operating mechanism by actuating the solenoid 89 to strike the arm 83 of the bellcrank 82. The solenoid may be actuated in response to the energization of the electromagnet 90 upon the occurrence of predetermined conditions or in response to a movement of the manually operated lever 92 to force the bar 98 and the solenoid 89 into engagement with the arm 83 of bellcrank 82 to rotate it in a counterclockwise direction about its pivot point 84. When the bellcrank 82 is rotated, the latch 80 is moved out of engagement with the lever 66 and at the same time the projection 88 carried on the arm 83 strikes the projection 90 carried by the lever 66 and causes a positive rotation of the lever 66 in a clockwise direction about its pivot pin 68.

The clockwise movement of the lever 66 about its pivot point causes the notched end 70 of the lever 66 to release the L-shaped engaging member 56. Since the reactive pressures of the biased actuating mechanism acting through the trip-free roller 22 are greater than the biasing force of spring 60, the engaging member 56 rotates in a clockwise direction about its pivot point 58 to disengage the roller 22.

When the roller 22 is disengaged, the lever 18 rotates in a counterclockwise direction about its pivot point 26 to the position shown by the dotted lines in Fig. 1 or as illustrated in Fig. 5. During this movement of lever 18, the roller 22 clears the sliding contact surface 108 of the pawl 104 and the pawl is biased by means of the spring 110 in a clockwise direction about its pivot point 106 to contact the L-shaped engaging member 56. Since the spring 110 is stronger than the spring 60, the pawl exerts a pressure against the engaging member 56 sufficient to cause the engaging member to rotate in a clockwise direction about its pivot point 58 to a position where the engaging member 56 is inoperative for retaining the roller 22.

As the lever 18 moves to the unlatched position shown in dotted lines in Fig. 1, or as shown in Fig. 5, the projection 38 on the end of the lever 18 contacts the projection 38 on the latch 34 and causes the latch to rotate in a clockwise direction about its pivot point 40 to release the pivot pin 26. When the latch 34 releases the pin 26, the spring 30 forces the links 24 to the position shown in dotted lines in Fig. 1 and as shown in Fig. 6. Since the lengths of the lever arms between the pivot pins 26 and 28, and 26 and 20 are fixed, the movement of the levers 24 to the position shown in Fig. 6 causes the lever arms 18 to rotate in a clockwise direction to a position where the roller 22 carried by the levers 18 is in its latched position in alignment with the fixed pivot point 28.

As the roller 22 approaches its latched position, it engages the sliding contact surface 108 of the pawl 104 and causes it to rotate in a counterclockwise direction about its pivot point 106 compressing the spring 110 and removing the biasing force on the engaging member 56. When the biasing force exerted by the pawl on the lever 56 is removed, the lever 56 is biased in a counterclockwise direction by reason of the spring 60 to the position where it engages the roller 22 to retain it in the latched position.

As the engaging member 56 rotates to its en-

gaging position, the top surface 57 of the lever 56 slides along the under-surface 61 of the lever 66 to a position where the notch 70 of the lever 66 engages the cooperative surface 72 of the L-shaped engaging member 56 to retain the lever 56 in its engaging position with the roller 22.

The movement of the lever 66 into its engaging position with the L-shaped member 56 causes the latch 80 of the bellcrank 82 to lock the lever 66 in its engaging position with the lever 56 since the bellcrank 82 is biased to its latched position by means of the spring 76. When the latching mechanism is in this position, the roller 22 is retained in its latched position in alignment with the pivot pin 28 of the links 24.

In order to actuate the circuit interrupter to a closed position, the electromagnet 44 may be energized in any of the well known manners to actuate the solenoid 42 and pull down on the levers 18 and 24 to cause them to rotate in a counterclockwise direction about their concentric pivot points 22 and 28. When actuated in this manner, the levers 18 and 24 are returned to the closed circuit position where the pivot pin 26 is engaged by the latch 34. Since the contact members (not shown) of the circuit interrupter are actuated in response to a movement of the operating bar 16 which is pivotally linked to the lever 18, it is evident that a movement of the lever 18 to the position as described actuates the contact members to a circuit closing position.

The notches 80 and 70 on the bellcrank 82 and the lever 66, respectively, are very slight, being less than three thirty-seconds of an inch deep, so that when the bellcrank 82 is actuated to unlatch the lever 66, a slight movement of the bellcrank 82 and the lever 66 effects a tripping of the engaging member 56 to release the roller 22. It is to be noted that the members of the latching mechanism are mounted on the frame independently of each other and are so disposed that when in the latched position they balance the reactive pressures exerted by the biased operating mechanism of the circuit breaker. Since it is only necessary to move the respective members of the latching mechanism through a very small arc to effect the release of the trip-free bar, it is evident that the mass movement of the members will be small.

By arranging the members in this manner, it is possible to decrease the time in which a movement of the trip-free roller to a tripped position is initiated to less than one-half a cycle from the time the tripping movement of the latching mechanism is initiated as compared to the period of time of some three to five cycles necessary where the latching mechanisms of the prior art are employed.

Although this invention has been described with reference to a particular modification thereof, it is, of course, to be understood that this invention is not to be limited, except insofar as is necessitated by the prior art and the scope of the appended claims.

We claim as our invention:

1. In a latching mechanism for a circuit interrupter provided with a member biased to an open circuit position for effecting a switching operation, in combination, means biased to releasably engage the member to restrain it in a predetermined position, a spring biased arm disposed for cooperative engagement with the bar engaging means to partially balance the reactive pressures from the biased member, a latch for locking the arm to lock the bar engaging means to

retain the biased member in a predetermined position, said engaging means, said arm and said latch each having a relatively small mass and each disposed for a small amount of movement to provide for a high speed tripping operation.

5. In a latching mechanism for a circuit interrupter provided with an operating mechanism biased to an open circuit position for effecting a switching operation, the operating mechanism including a trip free bar, in combination, a spring biased means biased to engage the trip free bar to retain it in a predetermined position, a spring biased means disposed to maintain the spring biased retaining means in an inoperative position against its bias until the trip free bar is in a predetermined position, a spring biased arm disposed for cooperative engagement with the spring biased bar engaging means to retain the bar engaging means in its operative position engaging the trip free bar, a latch for locking the arm to lock the bar engaging means to retain the trip free bar in a predetermined position.

6. In a latching mechanism for a circuit interrupter provided with an operating mechanism biased to an open circuit position for effecting a switching operation, the operating mechanism including a trip free bar, in combination, means releasably engaging the trip free bar to retain it in a predetermined position, a spring biased arm disposed for cooperative engagement with the bar engaging means to partially balance the reactive pressures from the biased operating mechanism, a latch for locking the arm to lock the bar engaging means to retain the trip free bar in a predetermined position, means operable to trip the latch, and means carried on the latch for providing a positive movement of the arm to disengage the bar engaging means and permit it to move in response to the reactive pressures from the biased operating mechanism to release the trip free bar when the latch is tripped.

7. In a latching mechanism for a circuit interrupter provided with an operating mechanism biased to an open circuit position for effecting a switching operation, the operating mechanism including a trip free bar, in combination, means biased to releasably engage the trip free bar to restrain it in a predetermined position, a spring biased arm disposed for cooperative engagement with the spring biased bar engaging means to partially balance the reactive pressures from the biased operating mechanism, a latch for locking the arm to lock the bar engaging means to retain the trip free bar in a predetermined position, and means operable to trip the latch to release the spring biased arm from its cooperative engagement with the spring biased engaging means and permit the reactive pressures from the biased operating mechanism to actuate the engaging means to release the trip free bar.

8. In a latching mechanism for a circuit interrupter provided with an operating mechanism biased to an open circuit position for effecting a switching operation, the operating mechanism including a trip free bar, in combination, means for releasably engaging the trip free bar to retain it in a predetermined position, a spring biased arm disposed for cooperative engagement with the bar engaging means to partially balance the reactive pressures from the biased operating mechanism, a latch for locking the arm to lock the bar engaging means to retain the trip free bar in a predetermined position, means operable to trip the latch, and means carried on the latch adapted to exert a force on the spring biased arm

during a tripping of the latch for providing a positive movement of the arm to disengage the bar engaging means and permit it to move in response to the reactive pressures from the biased operating mechanism to release the trip free bar.

9. In a latching mechanism for a circuit interrupter provided with an operating mechanism including a plurality of elements biased to an open circuit position for effecting a switching operation, in combination, means for engaging an element of the operating mechanism for retaining it in a predetermined position, means biasing said engaging means to engaging position, means operative to trip the engaging means to cause it to release the element of the operating mechanism and permit movement of the mechanism to the open circuit position, and means for biasing the engaging means to an inoperative position to retain the element until the element is returned to the predetermined position.

10. In a latching mechanism for a circuit interrupter provided with an operating mechanism including a plurality of elements biased to an open circuit position for effecting a switching operation, in combination, means for engaging one of said elements to retain the mechanism in a predetermined position, means biasing said engaging means to engaging position, means operative to trip the engaging means to release the element of the operating mechanism and permit movement of the mechanism to the open circuit position, and means disposed to maintain the engaging means in an inoperative position to retain the element until the element is returned to the predetermined position.

11. In a latching mechanism for a circuit interrupter provided with an operating mechanism including a plurality of elements biased to an open circuit position for effecting a switching operation, in combination, means for engaging one of said elements to retain the mechanism in a predetermined position, means biasing said engaging means to engaging position when the mechanism is in said predetermined position, means operative to trip the spring biased engaging means to release the element of the operating mechanism and permit movement of the mechanism to the open circuit position, and spring biased means disposed to maintain the spring biased engaging means in an inoperative position to retain the element until the element is returned to the predetermined position.

12. In a latching mechanism for a circuit breaker provided with an actuating member biased to open circuit position to effect interruption of the circuit, a pivoted main latch biased to latching position for engaging and restraining said actuating member in a predetermined position, a pivoted spring biased arm having a narrow shoulder for engaging and restraining said main latch in latching position, a light load latch for engaging and locking said arm to lock said main latch in latching position, means for moving said light load latch to released position to effect release of said arm, said light load latch having means for positively engaging and moving said arm to release the same from its engagement with said main latch upon movement of said light load latch to released position.

13. In a latching mechanism for a circuit breaker provided with an actuating member biased to an open circuit position to effect a switching operation, in combination, a main latch biased to engage said member to restrain it in a predetermined position, a movable arm biased to engage and restrain said main latch in latching position, and means carried on the movable arm to exert a force on the main latch to release the same from its engagement with said main latch upon movement of said movable arm to released position.

gage said latch to partially balance the component of the biasing force tending to move said latch to releasing position, a latch for locking said arm to lock said main latch to restrain said actuating member in said predetermined position, said arm and latch having relatively small mass and being disposed for a small amount of movement to effect release of said member.

5 11. In a latching mechanism for a circuit breaker provided with an actuating member biased to open circuit position to effect a circuit opening operation, in combination, a main latch having a latching position for engaging said actuating member to restrain it in a predetermined position, means biasing said latch to latching position, a spring biased arm for engaging said latch in its latching position to partially balance the component of the biasing force on said member tending to move the latch to 10 releasing position, a light load latch for locking said arm to lock said main latch in latching position, to restrain said actuating member, and means holding the main latch in an inoperative position until said actuating member reaches said 15 predetermined position.

20 12. In a latching mechanism for a circuit breaker provided with an actuating member biased to open circuit position to effect opening of the circuit, a pivoted main latch biased to a 25 latching position for engaging and restraining said member in an inoperative position, a spring biased pivoted arm having a narrow latch surface for engaging and restraining said main latch in its latching position, a light load spring biased 30 latch for locking said arm to lock said main latch in latching position, a spring biased pawl controlled by said actuating member for maintaining 35

said main latch in released position to prevent resetting of said arm and light load latch until said actuating member is returned to said inoperative position following its release.

13. In a latching mechanism for a circuit breaker provided with an actuating member biased to open circuit position to effect interruption of the circuit, in combination, a main latch having a latching position for engaging said member to restrain it in inoperative position, 10 means biasing said main latch to latching position, a spring biased arm for engaging said main latch to restrain it in latching position, a light load latch for locking said arm to lock said main latch in latching position, and a spring biased 15 means controlled by said actuating member for holding said main latch in released position until said actuating member reaches said inoperative position.

14. In a latching mechanism for a circuit breaker provided with a spring biased actuating member releasable to effect opening of the circuit, in combination, a main latch having a latching position for engaging and restraining said actuating member in a predetermined position, means biasing said latch to latching position, a spring biased arm for engaging and restraining said main latch in latching position, a spring biased light load latch for locking said arm to lock said main latch in latching position, 30 means including a member controlled by said actuating member for maintaining said main latch in inoperative position until said actuating member is returned to said predetermined position following each release of the same. 35

JOHN B. MACNEILL.

JOHN W. MAY.
